INKING DEVICE

Heinrich E. Haase, Chicago, Ill., assignor to Industrial Patents Corporation, Chicago, Ill., a corporation of Delaware

Original application December 7, 1936, Serial No. 114,689. Divided and this application July 8, 1937, Serial No. 152,641

1 Claim. (CL. 101—363)

This invention relates to an improved printing device.

This application is a division of my application entitled Printing device, Serial No. 114,689, filed December 7, 1936.

One of the objects of the invention is to provide an improved printing device.

Another object of the invention is to provide a printing device having an improved ink feeding means.

Other objects of the invention will be apparent from the description and claim which follow.

Attempts have been made from time to time to mark sausage products in various ways. Direct printing upon natural sausage casings prepared from animal intestines has been inherently fraught with difficulties due to the nature of the tissue. For example, natural casings prepared from animal intestines, because some of the fibers are shorter than others, are more or less in the form of a helix. Such casings cannot be flattened into a smooth plane and consequently are not adapted for printing with a flat bed type of printing press.

In accordance with the present invention, a single thickness of the casing is moved in contact with the printing means. This is accomplished by individually stirring and supporting the casings over a curved cylindrical surface fixedly secured relative to a rotatable printing roller. The casings are mechanically stretched at the immediate point of printing to assure a flat smooth printing surface.

Reference is had to the drawing in which like characters of reference are used to designate similar elements.

Figure 1 is a side view, partly in section, of a printing device constructed in accordance with the present invention.

Figure 2 is a front view of the device shown in Figure 1.

Figure 3 is a plan view of the device shown in Figure 1.

Figure 4 is a sectional view taken on line 4—4 of Figure 1 illustrating the means for stretching the casing at the point of contact with the printing roller.

Figure 5 is a detail plan view showing the inking roller mechanism.

Figure 6 is a side view of the mechanism shown in Figure 5.

Figure 7 is an enlarged detail view showing the printing roller mechanism.

In the drawing, a cylindrical mandrel 1, of metal or other suitable material, is shown rigidly

secured at one end to supporting frame 2, which is bolted or otherwise secured to floor 3. Mandrel 1 is curved substantially in the form of a goose neck for suitably carrying the helically formed casings.

Mandrel 1, at a suitable point between its ends, is provided with stop element 4 and, approaching its free end 5, is gradually flattened on its upper surface, as at 6, to provide a smooth flat surface at the point of printing. Intermediate the flattened portion 6, mandrel 1 is recessed at 7 for mounting shaft 8 and bearing roller 9. The peripheral surface of roller 9 rotates slightly above the surface 6 and in contact with the casings as they pass thereover.

On its lower surface and to either side of roller 9, as at 10 and 11, mandrel 1 is suitably tapered toward its free end 5. Clusters of relatively stiff bristles 12 or other resilient material, are suitably mounted to extend from the surface of tapered portions 10 and 11 and thus serve to stretch the tubular casings as they are moved relative to the immediate point of printing.

Printing assembly 13, comprising assembly frame 14 and printing roller 15, is pivotally mounted, as at 16, to supporting frame 2 for movement from and toward mandrel 1.

Printing roller 15 is pinioned to shaft 17 journaled in bearings 18 bolted, or otherwise secured, to assembly frame 14. Shaft 17 is rotatably driven by power transmitted from motor 19 through the agency of shaft 20, worm 21 and worm wheel 22. Motor 19 is bolted, or otherwise secured, to standard 23 suitably mounted on assembly frame 14.

As shown in Figure 7, printing roller 15 comprises a central printing band 24 carrying type designating suitable indicia and, at its outer peripheral edges, is annularly flanged to provide bearing surfaces 25. Roller 9 is provided with central area 26 having an outer covering of composition rubber 27 or other suitable resilient material and, like printing roller 15, is annularly flanged at its outer peripheral edges to provide bearing surfaces 28.

In practice, the casings 29 are individually stirred and supported over mandrel 1 against stop element 4. The forward end of casing 29 is left extending slightly beyond roller 9 whence it is suitably stretched by bristles 12 and ready for printing at that point. Assembly frame 14, mounting printing assembly 13, is then pivoted toward mandrel 1 and, as shown in Figure 7, printing roller 15 is moved into contact with the casing against the roller 9.

The bearing surfaces 25 of rotating printing roller 15 serve to frictionally press the casing against the bearing surfaces 28 of roller 9 and thus feed the casing from the mandrel during printing of the casing by band 24 against resilient surface 27 of roller 9. The tension of printing roller 15 against the casing moved over roller 9 may be regulated by weight 30 so as not to cut the casing. Weight 30 is adjustably mounted on shaft 31 to counterbalance the weight of the printing assembly 13 at pivotal point 16.

Ink from reservoir 32 is gradually but continuously applied to the type of printing band 24 through the medium of inking roller 33 and doctor rollers 34, 35 and 36. Roller 36 is rigidly secured to shaft 37 journaled in bearings 38. Roller 35 is rigidly secured to shaft 39 journaled for slideable longitudinal movement in bearings 40. Roller 34 is rigidly secured to shaft 41 journaled for slideable longitudinal movement in bearings 42. Bearings 38, 40 and 42 are each suitably secured to assembly frame 14. Roller 36 is rotatably driven by frictional engagement with printing roller 15, roller 35 by frictional engagement with roller 36 and roller 34 by frictional engagement with roller 35.

In practice, roller 36 is rotated in a constant plane against the type of printing band 24 of roller 15 while rollers 34 and 35 are longitudinally moved relative to each other and relative to roller 36 so as to provide an even distribution of the ink before its application to printing band 24. To accomplish this, shafts 39 and 41 are each provided with grooved rollers 43 and 44 for the reception of ball ends 45 and 46 of shaft 47 pivotally mounted, as at 48, on standard 49 bolted, or otherwise secured, to assembly frame 14. Pivotal movement is imparted to shaft 47 through the medium of rocker 50, crank 51 and connecting rod 52. Crank 51 is rigidly secured to shaft 53 journaled in bearings 54. Shaft 53 is rotatably driven by power transmitted from shaft 17 through the medium of sprockets 55 and 56 and chain 57.

Ink from reservoir 32 is intermittently fed to roller 34 through the medium of roller 33. Roller 33 is rotatably mounted to extend below

reservoir 32 and when rotated serves to carry a thin film of ink from reservoir 32. Reservoir 32 is rigidly secured to arm 58 pivotally mounted, as at 59, to standard 60 and is adapted for movement from and toward roller 34. Standard 60 is 5 rigidly secured to assembly frame 14. Pivotal movement of arm 58 and thus the reservoir 32 is controlled through the medium of roller 61 in contact with rotatable cam 62. Cam 62 is rigidly secured to shaft 63 journaled in bearings 64. Shaft 63 is rotatably driven by power transmitted from shaft 53 through the mesh of gears 65 and 66.

When dwell 67 of cam 62 is rotated in contact with roller 61, reservoir 32 is moved toward roller 15 15 34 whence roller 33 will contact roller 34, be rotated by roller 34 and thus deliver a supply of ink to roller 34. The ink supply to roller 34, as hereinbefore explained, will be evenly distributed over the surfaces of rollers 35 and 36 and thus be carried to printing band 24.

The present invention has been described as applied to the printing of natural sausage casings by way of illustration. It will be understood that the invention is also applicable to printing 25 synthetic sausage casings made from cellulosic material and other tubular articles regardless of the materials from which manufactured.

I claim:

In a printing device including an ink applying roller, means for intermittently applying ink to the ink applying roller comprising an overhead ink reservoir having a bottom opening therein, a freely rotatable feed roller rotatably mounted in said opening, means including an 30 arm pivotally mounting the ink reservoir for movement from and toward the ink applying roller and cam means engageable with the arm, said cam means being operable to permit movement intermittently of the feed roller into positive periodical rotatable contact with the ink applying roller to deposit ink thereon and to positively remove the feed rollers from the ink applying roller following the deposit of the ink thereon. 40

HEINRICH E. HAASE. 45
